ELECTRIC CONTROL PANELBOARD OR SIMILAR ARTICLE

Jacob Goldstein, Yonkers, N.Y., assignor to Murray Manufacturing Corporation, Brooklyn, N.Y., a corporation of New York

Filed Mar. 6, 1962, Ser. No. 69,102

Term of patent 14 years

(Cl. D26—13)

FIGURE 1 is a perspective view showing the front and two side surfaces of the electric control panelboard or similar article, the back surface being plain and flat and the other two side surfaces being identical respectively with opposite side surfaces;

FIG. 2 is another perspective view thereof.

FIGURE 3 is a front perspective view with the cover opened.

The essential features of my design reside in the portions shown in solid lines.

The design is characterized by the flush door in the raised face surface of the enclosure, and the door is

contoured on the side opposite the hinged side with an access opening for the fingers, all as shown.

I claim:

The ornamental design for an electric control panelboard or similar article, substantially as shown and described.
